UNITED STATES PATENT OFFICE.

BRADLEY WOODHULL, OF SCRANTON, PENNSYLVANIA.

DESIGN FOR A LINING-PLATE FOR STOVES OR RANGES.

SPECIFICATION forming part of Design No. 33,695, dated December 11, 1900.

Application filed October 24, 1900. Serial No. 34,216. Term of patent 14 years.

To all whom it may concern:

Be it known that I, BRADLEY WOODHULL, of Scranton, in the county of Lackawanna, State of Pennsylvania, have invented and 5 produced a new and original Design for Lining-Plates for Stoves or Ranges, of which the following is a specification, reference being had to the accompanying drawings, forming part thereof.

10 In said drawings, Figure 1 is a vertical section through a lining-plate embodying my new design. Fig. 2 is a front elevation of the same.

As shown in the drawings, the leading or material feature of my design consists of a

projection A on the face of the lining-plate 15 B, the said projection being wedge shape in cross-section, as shown in Fig. 1, and with the top C and side walls D inclined inwardly, as shown in Fig. 2. The face of the lining-plate surrounding the projection is left plain and 20 flat.

I claim—

The design for a lining plate as herein shown and described.

BRADLEY WOODHULL.
